GAMEBOARD

Beverly W. Taylor, Hermann, Mo. 65041

Filed Oct. 4, 1966, Ser. No. 4,156

Term of patent 7 years

(Cl. D34—5)

FIG.1

FIGURE 3 is a view in perspective of the base portion shown in dotted lines so that the complete article is disclosed.

The dominant features of my design reside in the full line portions shown.

This application is a continuation-in-part of application Ser. No. D. 84,726, filed April 12, 1965, now abandoned.

I claim:

The ornamental design for gameboard, as shown and described.
